COUNTING APPARATUS

Walter Abel, Salford, England, assignor of one-half to Measure Meters Limited, Salford, England, a body corporate of Great Britain, and one-half to Dobson & Barlow Limited, Bolton, England, a body corporate of Great Britain

Application September 18, 1950, Serial No. 185,366
In Great Britain September 21, 1949

4 Claims. (Cl. 235—144)

1

This invention concerns counting devices having a series of intergeared wheels or discs mounted on a common shaft, each wheel or disc bearing numerals 0 to 9 on its periphery, and relates particularly to improvements in such devices in which counting wheels or discs after being actuated can be returned to zero by the depression of a setting lever.

One object of the present invention is a counting device of the aforesaid kind in which the numbered counting wheels can be set to any predetermined number within the range of the device and which will be actuated from that number back to zero, and when all of the counting wheels are in their zero positions, a switch or other controlling device will be actuated for stopping a machine or for other purpose.

A further object of the invention is to provide a novel construction of the counting wheels whereby each counting wheel can be set to a desired number, and after all the counting wheels have returned to their zero positions the operation of the setting lever will return all the counting wheels to their predetermined numbers, thereby re-setting the device for the next counting operation. The device will therefore continue to operate the switch or other controlling device after the same number of actuations for any number of times, until the setting of the counting wheels is altered to another desired number.

The invention is illustrated in and will be described with reference to the accompanying drawings, in which:

Fig. 1 is a side elevation of the counting device with the casing removed,

Fig. 2 is a section on line 2—2 of Fig. 1 but with the casing in position,

Fig. 3 is a section on line 3—3 of Fig. 1 with the casing removed,

Fig. 4 is a plan of Fig. 1 with the casing removed,

Fig. 5 is an exploded view of the drive from the actuating shaft to the first counting wheel,

Figs. 6 to 14 are detail views of the parts shown in Fig. 5,

Fig. 15 is a detail view of the last counting wheel,

Fig. 16 is perspective view of the lever operating the switch or other controlling device.

The counting device shown in the drawings has four counting wheels A¹, A², A³ and A⁴ each having the numerals 0 to 9 on its periphery, A¹ being the "units" wheel, A² the "tens" wheel, A³ the "hundreds" wheel, and A⁴ the "thousands"

2

wheel. The device can thus be used for counting up to 9999. It is to be understood however that the device is not limited to four counting wheels and that it can be provided with any desired number of counting wheels.

The counting wheels A¹ to A⁴ are loosely mounted on the shaft A and the "units" wheel A¹ receives its motion from the shaft B which is rotatably mounted in bearings b carried by the base B¹ of the device. Shaft B projects through one end of a casing C suitably secured to the base B¹. The shaft B is driven from the device or other apparatus which it is desired that the device should control. Thus, in the case of a device for measuring predetermined lengths of fabrics, the shaft B would be driven from the measuring rollers between which the fabric is passed.

The shaft B drives the counting wheel A¹ through a pinion b¹ on the shaft B which drives the pinion a loosely mounted on the shaft A, the boss a¹ of the pinion a being eccentric (see Fig. 8). A pin toothed wheel a² (see Fig. 9) is mounted on the eccentric boss a¹ of the pinion a so that as the latter rotates, the wheel a² is reciprocated to bring the teeth thereof into engagement with the horizontal slots a³ in the boss of a toothed wheel a⁴ loosely mounted on the shaft A (see Fig. 10). Thus for each revolution of the pinion a the wheel a⁴ is rotated an angular distance equal to the distance between two slots a³. The movement of the wheel a² is guided by a slotted plate a⁵ secured to the wheel, the slot in which is a loose fit over the shaft B. The wheel a drives the wheel a⁶ through the carrier pinion d loose on a shaft D, and the wheel a⁶ (Fig. 11) has a pinhole a⁷ in which engages a pin a¹⁴ projecting from the heart shaped cam a⁹ carried by the wheel a¹⁰ which is the units counting wheel.

Instead of the numerals of the units counting wheel A¹ being inscribed directly on the periphery of the wheel a¹⁰, they are inscribed on a disc a¹¹ (Figs. 5 and 13) mounted on the hub of the wheel a¹⁰ and having a ring of internal ratchet teeth a¹² which are engaged by the spring and ball catch a¹³, Fig. 12. This allows of the disc a¹¹ being rotated in one direction in relation to the wheel a¹⁰ and the cam a⁹ carried thereby, and driven in the opposite direction by wheel a¹⁰. The whole of the mechanism shown exploded in Fig. 5 and described above is held in position on the shaft A by the spring clip e (Fig. 14) its position being located by distance pieces e¹ (Fig. 7).

The disc a¹¹ forming the unit counting wheel A¹ drives the "tens" counting wheel A² in the

usual way by the engagement of the slot a^{13} with the pinion d^2 loose on the shaft D which in turn engages the teeth of the wheel A². Instead however of the numerals of the wheel A² being inscribed directly on the periphery of the wheel A² they are inscribed on a disc at the side of the wheel and connected thereto by internal ratchet teeth and spring and ball catch exactly as described with reference to the units wheel A¹. The "hundreds" wheel A³ is driven from the "tens" wheel A² in the same way through the pinion d³ as the wheel A² is driven from the units wheel A¹ and the "thousands" wheel A⁴ is driven from "hundreds" wheels A³ through the pinion d⁴ in the same way, each of the toothed pinions of the wheels A², A³, and A⁴ carrying a heart shaped cam a⁹ and the inscribed portion of each wheel being capable of being rotated in one direction in relation to its toothed portion and the cam a⁹ carried thereby.

The periphery of the inscribed disc portion of the last counting wheel A⁴ is formed with a recess a⁴¹ as shown in Fig. 15, this recess being so positioned that it is opposite the end of the arm f of the pivoted stirrup shaped lever F (see Fig. 16) when the zero of the wheel A⁴ has moved rearwardly a very small angular distance from the normal zero position.

The stirrup shaped lever F is pivoted on a rod F¹ near the base B¹ and is out of balance, so that when the end f can enter the slot a⁴¹ in the wheel A⁴ the longitudinal member f¹ will fall a short distance. The member f¹ carries a projection f² which controls a micro-switch indicated at G so that when the member f¹ of the lever F falls it operates the switch which in turn, through a suitable relay, operates to stop a machine or carry out some other function. As shown in Fig. 16 the projection f² is eccentrically mounted on the member f¹ so that it can be finely adjusted in relation to the contact member of the switch G which it controls.

The end f³ of the second arm of the lever contacts an arm G¹ (Fig. 6) having a catch g which normally engages a recess h in the periphery of a disc h¹ secured on a shaft H to which the resetting handle H¹ is affixed, thereby only allowing a limited movement of the shaft H unless the member f¹ of the lever F has fallen owing to the end f having entered the slot a⁴¹ in the wheel A⁴.

The shaft H carries a finger h² at each end which fingers bear against the shaft D the ends of which are mounted in arcuate slots in the ends B² of the frame, and these fingers h² press on the shaft to keep the pinions d², d³ and d⁴ in contact with the teeth of the counting wheels A², A³ and A⁴, respectively, against the action of the light spring h³ tending to move the shaft D in the arcuate slots to disengage said pinions from the respective counting wheels.

The shaft H has also a number of arms k affixed to it, there being an arm k for each counting wheel A¹ to A⁴. The arms k normally lie below the respective heart shaped cams a⁹, and if the shaft H is rotated by the lever H¹ a second portion k¹ at the end of each arm engages the corresponding cam a⁹ and returns it with the counting wheel and the numbered disc to the zero position, i. e. the position shown in Fig. 3.

The counting mechanism is enclosed by a casing C secured to the base B¹ and having an aperture m at the top immediately over the counting wheels A¹ to A⁴, the micro-switch G being

carried on the outside of the casing C, and the micro-switch G is enclosed by a cover N having a hinged member n which covers the aperture m in the casing C. The hinged member n has a window n¹ through which the counting wheels A¹ to A⁴ can be viewed when the member n is turned down on to the top of the casing C.

To set the counting wheels so that the lever F will fall to control the micro-switch G after a predetermined number of operations or a predetermined length has been measured, all the counting wheels A¹ to A⁴ are moved to their zero positions, which in the device described and shown, is at the top immediately below the aperture m in the casing, and when in this position, each of the heart cams a⁹ is in the vertical position shown in Fig. 3. The hinged member n is then raised and the predetermined figure at which it is desired the mechanism should operate is brought below the aperture m by manually rotating the relevant numbered discs a¹¹ relatively to the wheels a¹⁰ to which the heart shaped cams a⁹ are fixed, whereby the zero position of the heart shaped cams is not altered. In the drawings, the desired number is shown as 25, so that the discs a¹¹ of the "units" wheel A¹ and the "tens" wheel A² have been moved to bring the 5 of the former and the 2 of the latter into line with the 0 of the wheels A³ and A⁴ without moving the cams a⁹ of any of the wheels from their zero positions. When the counting wheels have been set the recess a⁴¹ in the disc of the last counting wheel is just clear of the end f of the pivoted stirrup shaped lever F, so that the latter is held with its member f¹ in the raised position with the end f³ of its second arm in engagement with the arm G¹ to retain the catch g in the recess h of the sleeve h¹ secured to the shaft H, thereby preventing rotation of the latter by the re-setting lever H¹ except for the small angular distance equal to the length of the recess h. This small angular distance is sufficient to allow movement of the shaft D in its arcuate bearing slots under the influence of the springs h³ to disengage the pinions d², d³ and d⁴ from the counting wheels A² respectively and to A⁴ to allow of the initial setting of the latter to their zero positions but insufficient for the arms k to engage the heart shaped cams a⁹.

The rotation of the shaft B is in a direction to drive the counting wheels backwards so that after two and five-tenths of a revolution of the wheel A¹, this wheel and also the wheel A² have been returned to their zero positions whereby all the numerals of all the counting wheels show zero. When the wheels A¹ and A² show zero however, their heart shaped cams a⁹ are not in their zero positions, they having been moved therefrom five-tenths and two-tenths of a revolution respectively as will be understood from the previous description. A very small further backward movement of the counting wheel A¹ from its zero position is immediately transmitted through the wheels A² and A³ to the wheel A⁴ opposite the end f of the pivoted stirrup shaped lever F, allowing the member f¹ thereof and thereby fall to cause the micro-switch to operate to carry out its purpose of stopping a machine or other function. The falling of the member f¹ of the lever F also causes the disengagement of the catch g on the arm G¹ from the recess h in the disc h¹ secured to the shaft H and thereby allow the rotation of the latter to its full extent by the re-setting lever H¹.

When it is desired to reset the counting mech-

anism to again count 25 operations or units of length, the resetting lever H^1 is operated to rotate the shaft H , which causes the finger k^1 to move the heart shaped cams a^9 of the counting wheels A^1 and A^2 back to their zero positions corresponding to the numerals 5 and 2 on these counting wheels, so that the counting mechanism is reset to 25. The rotation of the cams a^9 and the wheels to which they are affixed is allowed owing to the pressure of the fingers h^2 having been removed from the shaft D owing to the disengagement of the end f^3 of the lever F from the arm G and the consequent disengagement of the catch g from the recess h in the disc h^1 , so that the shaft D is retracted by the springs h^3 to bring the pinions d^2 out of engagement with the teeth of the counting wheels.

The counting wheel A^4 will also be moved by the action of its finger h^2 on its cam a^9 the slight angular distance necessary to move the recess a^4 therein away from the end f of the lever F , so that the latter is moved about its pivot rod F^1 to raise the member f^1 thereby closing (or opening) the micro-switch G and also locking the shaft H which cannot again be rotated except for the slight angular movement, previously referred to, until the counting wheels A^1 and A^2 have again returned to their zero positions.

I claim:

1. In a counting device of the type referred to, the combination with counting wheels of different values and a switch for controlling a useful function, of an unbalanced two-armed pivoted lever of stirrup shape, a bar on which the said lever is pivoted, the end of one arm being adapted to enter a recess in the counting wheel of highest value when all the counting wheels have returned to zero, a projection carried on two members of the lever connecting the two arms, which projection operates the switch when the said end enters the recess in the counting wheel, resetting mechanism for resetting the counting wheels, and a spring loaded pivoted catch which normally prevents the operation of the re-setting mechanism, the movement of the lever when it engages in the said recess causing the second arm

to actuate the said catch to release the resetting mechanism.

2. A counting device as in claim 1, having a shaft parallel to the axes of the counting wheels, a plurality of levers, one for each counting wheel, secured on said shaft, the rotation of said shaft causing each lever to engage the corresponding wheel and return it to zero, and a disc secured on said shaft and provided with a recess on its periphery with which the catch locking the re-setting mechanism normally engages.

3: A counting device as in claim 2, having a spring loaded shaft parallel to the axes of the counting wheels, the ends of said shaft being mounted in arcuate slots, pinions transmitting the drive from one counting wheel to the next being mounted on said shaft, and fingers projecting from the shaft carrying the levers which re-set the counting wheels, and engaging the spring loaded shaft to hold the latter in a position with the said pinions in mesh with the counting wheels when the re-setting mechanism is not operated.

4. A counting device as in claim 3, having the recess in the disc engaged by the pivoted lever of sufficient angular length to allow of a small rotary movement of the shaft when the catch is engaged in the recess, such angular movement being sufficient to allow the fingers contacting the spring loaded shaft carrying the pinions to move a sufficient distance away from the spring loaded shaft so that the latter will move in its arcuate bearing slots to cause the disengagement of the pinions from the counting wheels for the purpose of setting the counting wheels to any desired number.
